UNITED STATES PATENT OFFICE.

JOSEF ANDERS BACKLUND, OF NEW YORK, N. Y.

PROPELLION OF VESSELS.

1,267,351.

Specification of Letters Patent. Patented May 28, 1918.

Application filed November 5, 1917. Serial No. 200,331.

To all whom it may concern:

Be it known that I, JOSEF ANDERS BACKLUND, a subject of the present Government of Russia, residing at 14 Continental Place,

5 Mariners Harbor, Staten Island, borough of Richmond, city and State of New York, have invented certain new and useful Improvements in the Propulsion of Vessels, of which the following is a specification.

10 This invention relates to boat propulsion, and especially to that class wherein one or more pistons are projected out into the water behind the boat, to propel the same.

One advantage of this invention is to apply 15 the power of a boat directly in line with its direction of motion by means of a piston head.

Another advantage is to provide a piston to directly act on the water without revolving 20 or causing the water to churn.

Another advantage is to provide a piston adapted to project into the water and which upon its return stroke permits air to pass through to its rear face in order to break the 25 bond between the piston and the water.

Further advantages and possibilities will become apparent as the specification proceeds. In the drawings, like numerals refer to the same parts throughout.

30 Figure 1 is a top or plan view of an apparatus embodying the present invention. Fig. 2 is a longitudinal section of Fig. 1 on line *c-d*. Fig. 3 is a sectional view of piston 2 of Fig. 1 on line *a-b*. Fig. 4 is a 35 modification in partial section.

When noting the wake of any mechanically propelled boat it is easily apparent that a great lack of efficiency is present in all known means of propulsion, for over a wide

40 area behind the boat and also for a considerable distance, the water swirls and churns powerfully in a manner strongly suggesting that an enormous amount of energy has been wasted in thus setting the water in commotion.

45 The present invention is designed to overcome this by avoiding rotation of projecting parts and the consequent enormous friction of rotation in the water.

50 Referring to the drawings the boat 34 has an interior bracing of girders 42 on which rests bed plate 43. This latter supports the bearings for the shafts of gears 24, 25, 26 and 27, also the flywheels 18 and 19. The 55 guide channels 32 and 33 in which the slide blocks 21 and 20 reciprocate are supported

by bed plate 43, likewise stand 15, and cylinders 1 and 3, whose intermediate webs provide bearings for propeller shaft 6, the space between the webs providing bilge basin 35. 60

The power shaft 6 has mounted upon it gears 9 and 10, and at its extremity propeller 5, which normally revolves just fast enough to follow the movement of the boat without resistance. The function of the propeller is to turn the boat or reverse its directions when setting out to sea. 65

When lever 17 is moved in the direction of the arrow it will communicate its motion to shifter 28 by link 13, causing gear 8 to mesh 70 with gear 10. The miter gears 25 and 27 will then revolve crank 23 and fly wheel 19. Link 30 will also reciprocate block 20 and this piston head 4.

Likewise, if lever 16 be moved to the left, 75 it will change shifter 29 by means of link 14 so that gear 7 will mesh with gear 9. Incidentally collars 11 and 12 retain gears 27 and 24 in their proper running positions.

Upon revolving gear 24, its mate 26 will 80 turn flywheel 18 and crank 22. This latter will cause block 21 to reciprocate by means of link 31. This, of course means that piston 2 is projected into the water and withdrawn continually. If an ordinary imperforate cylinder head were thus reciprocated its return movement would neutralize the projection strokes. In the present apparatus, however, air inlet valves 37 permit the inflow of air when the shaft 46 projects 85 90

head 2 outward into the position illustrated. Upon the return stroke, valves 37 close and the imprisoned air in chamber 44 passes through channels 40, and opening valves 39 outwardly, this air instantly breaks the 95 bond between rear face 45 and the water, and completely displaces the piston head in the water. Naturally the air floats up to the surface very speedily, leaving a fresh solid wall of water against which the face 45 100 may impinge with great effectiveness. The rear face 45 of the piston is concave for the purpose of gripping the water and preventing it from receding, thus producing the resistance and traction which is so desirable. 105 The concave face is provided with air outlets as previously described, which are preferably located in the positions illustrated.

Owing to the fact that water, and especially salt water has a very corrosive action 110 on exposed iron and steel, it is proposed to use suitable alloys in their stead. This may

also be accomplished by sheathing the exposed parts with the inert alloys. Also in cylinders 1 and 3 there are provided channels 41 to lubricate the piston. These channels as 5 well as propeller bearings 36 are provided with pipes 38 through which the proper lubricants are fed under pressure. One piston would give but isolated impulses to a boat propelled thereby, thus it is preferable to 10 use two or more alternating with each other to make the progress of the vessel more smooth. It is to be noted that in the views the rudder has been omitted. This is because the position of a rudder would be optional, 15 either above or below the propeller, and therefore superfluous of illustration, especially as the omission renders the drawings more clear.

In Fig. 4, is seen a slight improvement, 20 wherein it is intended to protect the surface of the cylinder from the water by means of an elastic fabric 48 or sheath of rubber secured on the cylinder under ring 49. This sheet rubber extends into the annular pocket 25 47 in casting 50, and expands and contracts linearly with the reciprocations of the piston. It is obvious that different modifications of this class might be introduced without departing from the invention. This is 30 also true in regard to changing the method of applying the power to the piston, as for example entirely omitting the gears, fly-wheels and cranks and substituting some other system therefor. Consequently I re-serve all rights to any and all such modifications.

Having thus fully described my invention I desire to obtain by Letters Patent.

1. A boat provided with a cylinder exposing an open end to the water, a piston mounted in said open end adapted to reciprocate outwardly into the water and into said cylinder, and a protective sheath secured to the exposed extremity of said pis-

ton surrounding the latter and extending to 45 the open end of said cylinder, said sheath attenuating and contracting in accord with said reciprocation.

2. A boat provided with a cylinder having a closed end extending into the boat and exposing an open end to the water, a piston adapted to project from said open end in reciprocal movement, air channels in said piston communicating with the interior of said cylinder and with the outside water, 50 vents in said cylinder communicating with the interior of said cylinder and the interior of said boat, means for breaking and establishing said communications at intervals and means for reciprocating said piston. 60

3. A boat provided with a cylinder having an inner closed end and exposing an open end to the water, a piston adapted to reciprocate in said cylinder and project from the open end into the water, a shaft secured to said piston passing through the closed end of said cylinder, and air intake valves situated in said closed end and communicating with the interior of said cylinder. 65

4. A boat provided with a cylinder exposing an open end to the water, and having an inner closed end provided with air inlet valves communicating with a chamber in said cylinder, a piston adapted to reciprocatively project from said open end into the water, air outlet valves in said piston adapted to open outwardly and means for reciprocating said piston. 70

Signed at 132 Nassau street, in the bor- 80 ough of Manhattan, county of New York, city and State of New York, this 15th day of October, 1917.

JOSEF ANDERS BACKLUND.
